Attorney, Agent, or Firm—Samuel G. Layton, Jr.

[57] CLAIM

The ornamental design for seat or similar unit of furniture, substantially as shown and described.

DESCRIPTION

FIG. 1 is a front perspective view of a seat embodying my new design;

FIG. 2 is a front perspective view of a second embodiment of the seat shown in FIG. 1;

FIG. 3 is a front perspective view of a third embodiment of the seat shown in FIG. 1; and

FIG. 4 is a front perspective view of a fourth embodiment of the seat shown in FIG. 1.

The rear surfaces of the seat not visible in FIGS. 1-4 are substantially plain and unornamented.
